ATTORNEYS.

UNITED STATES PATENT OFFICE.

SHERMAN T. ALLEN, OF LOS ANGELES, CALIFORNIA.

OSCILLATING SLEEVE-VALVE.

1,237,989.

Specification of Letters Patent. Patented Aug. 21, 1917.

Application filed December 6, 1916. Serial No. 135,450.

To all whom it may concern:

Be it known that I, SHERMAN T. ALLEN, a citizen of the United States, residing at Los Angeles, in the county of Los Angeles and State of California, have invented new and useful Improvements in Oscillating Sleeve-Valves, of which the following is a specification.

This invention relates to an internal combustion engine and particularly pertains to a valve construction therefor.

It is an object of this invention to provide a valve for admitting gaseous fuel into an engine cylinder and permitting the escape of exhaust gases therefrom, which will provide a rapid acting valve movement, and thereby insure the development of maximum power from the engine.

Another object of this invention is to provide a valve having oscillating valve sleeves which may be moved, without great effort, to open and close the valve ports and which may be actuated by a simple valve operating mechanism.

Another object is to provide an oscillating valve sleeve which will be so constructed as to reduce the height of the motor and provide an engine of compact and simple design.

Another object is to provide a valve sleeve which will permit the explosive gases within the cylinder to be ignited by a spark plug disposed in the cylinder head and extending downwardly therefrom, thereby insuring a thorough ignition within the cylinder.

Another object of this invention is to provide a valve sleeve adapted to oscillate and which is so constructed as to be insensitive to the strain produced by the valve actuating mechanism and at the same time permit the valve sleeves to expand in a manner to cause them to oscillate without leakage of the fuel.

Another object of this invention is to provide a valve sleeve which may be readily lubricated and mounted in its operative position.

It is a further object to provide a valve construction that may be embodied within the design of most engines without alteration of the essential features of the engine construction.

Other objects will appear hereinafter.

The invention is illustrated, by way of example, in the accompanying drawings in which:

Figure 1 is a view in plan illustrating an internal combustion engine and particularly disclosing the manner in which the valve operating mechanism is mounted thereupon. 60

Fig. 2 is a view in transverse vertical section illustrating in a detail manner the correlation of an engine cylinder, its piston, and the oscillating valve sleeve with which it is operatively connected. 65

Fig. 3 is a view in elevation illustrating the complementary sleeve members as disassociated from their mounting and particularly disclosing the bayonet joint with which the contiguous edges of each sleeve is 70 secured.

Fig. 4 is a view illustrating a fragmentary portion of the valve sleeves and disclosing the shape and disposition of the valve ports formed therethrough. 75

Fig. 5 is a view in transverse section as seen on the line 5-5 of Fig. 3 and illustrates the relation between the two oscillating valve members and their relative movement in relation to each other. 80

Fig. 6 is a view in section and elevation illustrating another manner in which the actuating arms may be constructed to oscillate the valve sleeves.

Referring to the drawings more particularly, 10 indicates an internal combustion engine provided with a series of cylinders 11 within which pistons 12 reciprocate and act upon piston rods 13 secured to the engine crank shaft in any preferred manner. 85 Reference being had to Fig. 2 of the drawings it will be seen that the upper end of the cylinder is open and formed with a counter-bore 14. This counter-bore is of a diameter to receive the lower projecting end of an outer oscillating valve sleeve 15 and an inner oscillating valve sleeve 16. These sleeves are formed with walls of a thickness to cause the inner diameter of the inner sleeve to be in alignment with the bore 95 of the cylinder and thereby making a continuation thereof. 100

The sleeves 15 and 16 are of similar construction and are cylindrical in shape and

of a length to properly prevent the leakage of gaseous fuel between them. The outer sleeve is provided with a transverse slot 17 through which the rocking lug 18 of the inner sleeve extends. This lug is in alignment horizontally with a similar lug 19 formed upon the outer face of the sleeve 15 and extending in an opposite direction thereto. These lugs are formed with recesses 20 adapted to receive the inwardly extending rounded ends of the shifting arms 21. These arms are secured upon shafts 22 and 23 which lie parallel and are provided in pairs to lie each side of the engine. Suitable bearings 24 are secured to the engine frame and slidably hold these shafts so that they may be reciprocated by a crank shaft 25 connected by pitman rods 26 to the shaft ends. This crank shaft extends transversely of the engine and is here shown as driven by a worm gear 27 in mesh with a gear 28 secured upon the crank shaft. In this manner the shafts 22 and 23 will be positively reciprocated and will oscillate the valve sleeves 15 and 16 to produce positive synchronization between the movement of the engine piston and its valve.

As a means of permitting the sleeves to resiliently adjust themselves in relation to each other, they are split throughout the width of their walls and formed with a bayonet joint. This joint is constructed by cutting a longitudinally extending slot 29 through the wall of the sleeve adjacent the edge of the split. This slot communicates with an opening of similar width through which a tenon 30 is placed. This tenon is formed with a reduced neck portion adapted to register with a reduced portion of the slot and has an enlarged T-shaped end which fits within the slot 29. It will thus be seen that any force acting upon the sleeves to produce tangential or radial movement of the sleeves will act without distorting the sleeves, due to their interlocked construction.

The outer sleeve is formed with an inlet port 31 and an outlet port 32, which are adapted to be moved to register with an inlet port 33 and an outlet port 34 formed through the inner sleeve. These ports, as disclosed in Fig. 4 of the drawings, are rectangular in shape and of a vertical height greatly in excess of their horizontal width, making it possible for them to open and close quickly and with a short range of movement. The port 31 of the outer sleeve and the port 34 of the inner sleeve are diametrically disposed in relation to each other, while the port 32 and the port 33 bear a similar relation to each other, although formed upon opposite sides of the center of the sleeves. In this manner the sleeves may be rotated in one direction to cause ports 31

and 33 to register, while rotation in the opposite direction will produce registration of ports 32 and 34. This, as will be understood, is accomplished by the movement of the shafts 22 and 23 and their arms 21.

The valve sleeves are suitably housed within a removable valve head 35 which is bolted by means of cap screws 36 to the upper open end of the cylinder block. This valve head is provided with an inlet opening 37 with which the ports 31 and 33 are adapted to register, and an outlet opening 38 with which the ports 32 and 34 are adapted to register. These openings communicate with the top of the cylinder through passage-ways 39 and 40 between which a threaded opening 41 occurs to receive a spark plug 42. In this manner the gaseous fuel will be permitted to pass into the cylinder from the cylinder head and pass out of the cylinder after explosion, through the cylinder head, thus permitting the proper scavenging of the cylinder and intake of fuel. The central disposition of the spark plug will cause the gaseous fuel to be thoroughly ignited and properly exploded. As illustrated in the drawings, the cylinder head is formed with water passage-ways 43 by which the head may be thoroughly cooled.

The modification disclosed in Fig. 6 of the drawings shows the lugs 18 and 19 as formed with a vertical opening through which a pin 44 extends. This pin is engaged by the ends of a slidable actuating arm 45 by which the valve sleeves are oscillated. The actuating arm 45 is formed with a cylindrical stem which is reciprocally mounted within a bore 46 formed in an arm 47 secured to the shafts 22 and 23. The bore 46 forms a pocket within which a coil spring 48 is positioned and adapted to bear against the inner end of the actuating arm 45. In this manner the shafts 22 and 23 may be reciprocated and the arm 45 vibrated so as to oscillate the sleeves, the spring 48 at all times causing the arm 45 to move with the pin 44 as it travels on its arc of oscillation.

In operation, the cylinder block, its head, and the oscillating valve sleeves are mounted as disclosed in Fig. 2 of the drawings, with the inner rounded ends of the actuating arms 21 in register with the recesses formed in the ends of lugs 18 and 19. As the shafts 22 and 23 are reciprocated by the crank shaft 25, lug 18 will be acted upon to oscillate the valve sleeve 16 in the direction of the arrow —a— of Fig. 5. Simultaneous with this action, the lug 19 will be acted upon to oscillate the sleeve 15 in the direction of the arrow —b—. This will bring ports 31 and 35 in register and cause ports 32 and 34 to swing from each other into a

positively sealed position. Reverse movement of oscillation to swing sleeve 16 in the direction of the arrow —*c*— and the sleeve 15 in the direction of the arrow —*d*— 5 will act to move ports 31 and 33 out of register and ports 32 and 34 into register. This movement is timed in accordance with the movement of the piston and will thereby act to alternately open an intake and exhaust 10 port, the bayonet joint construction of the sleeves preventing objectionable strains which would distort them and impair their proper operation.

It will thus be seen that the valve here 15 provided for use with internal combustion engines is simple and compact in its construction, may be readily oiled, and may be actuated in a positively timed manner to open and close the intake and exhaust ports

of an engine without damaging wear or dis- 20 tortion of the parts involved.

I claim:

An oscillating valve for internal combustion engines, comprising an outer split valve sleeve, an inner split valve sleeve positioned 25 within said outer sleeve, said sleeves having ports formed therethrough adapted to alternately register upon oscillation of the valve sleeves in relation to each other, and a bayonet joint with which the contiguous 30 edges of each of said sleeves is formed to allow expansion of the sleeve without subjecting it to the torsional strains produced by oscillation of said sleeves.

In testimony whereof I have signed my 35 name to this specification.

SHERMAN T. ALLEN.
